UNITED STATES PATENT OFFICE.

IDA HÄGGI, OF ZURICH, SWITZERLAND, ASSIGNOR TO ARDEAT A. G., OF HOHLSTRASSE, ZURICH, SWITZERLAND, A CORPORATION OF SWITZERLAND.

MAGNETO-ELECTRIC POCKET LAMP.

Application filed August 26, 1924. Serial No. 734,297.

This invention has for its object a magneto-electric pocket lamp provided with a tubular protecting casing within which is securely mounted an inducting magnet 5 adapted to be actuated by a driving gear and having fixed therein an inductor, the features of novelty in this apparatus consisting therein, that one of the axles or shafts axially arranged to and connected 10 with either end of the inductor serving for the production of the electric current is securely mounted in the closed end of the tubular casing, while on the opposite end of the inductor the second centre axle or 15 shaft is bolted to a casing containing the driving gear. In this way a connection between the inductor and the electric lamp is effected by means of a contact pin, the latter being fixed in an insulating sleeve mounted 20 in the second of the aforesaid axial shafts and, with one end of the anchor winding, being guided through a bore provided in the last named shaft. Simultaneously with this 25 operation an insulating contact device arranged in the driving gear casing is caused to make connection with the electric lamp of the inner electric circuit, while the outer circuit is led over the protecting casing. Further novel features consist in that the 30 driving gear casing, which comprises several parts, is held together by means of two screw-bolts, of which one is at the same time clamping a spring having the tendency to raise the bar of a rack from the driving gear 35 casing and make it engage with a pinion of the driving gear. The latter possesses a coupling comprising two coupling-wheels of which one is spring-controlled and made to engage with the other when the apparatus 40 is actuated. One of the coupling-wheels is furthermore meshing with a gear wheel which by means of intermediate gear wheels transmits its movement to a toothed wheel mounted with its flanged part in a flange 45 attached to the magnet. Owing to the screwing together of the several parts of the casing containing the driving gear by the aid of the screw-bolts the said gear is guided by and bearing in the casing and 50 prevented from displacement in an axial direction.

The accompanying drawings illustrate, by way of example, a form of construction in

which this invention may be carried out. In these drawings:—

55

Fig. 1 shows a side view of the protecting casing;

60

Fig. 2 shows a longitudinal section thereof, with certain inner parts, however, in elevation;

65

Fig. 3 represents a longitudinal section, partly in elevation, of the driving gear in a larger scale;

70

Fig. 4 is a section through the contact making device;

75

Fig. 5 is a cross section through line I—I in Fig. 1 seen from the right-hand side;

80

Fig. 6 is a cross section through line II—II in Fig. 1 seen from the right-hand side;

85

Fig. 7 is a cross section through line III—III in Fig. 1 seen from the right-hand side;

90

Fig. 8 is a cross section through line IV—IV in Fig. 1 seen from the left-hand side;

95

Fig. 9 is a cross section through line V—V in Fig. 1 seen from the left-hand side, and

100

Fig. 10 is a cross section through line VI—VI in Fig. 1 seen from the left-hand side.

105

Fig. 11 shows a side view and partly a sectional view of the driving gear and the contact making device respectively, and

110

Fig. 12 shows a section through the contact making device.

Figs. 13, 14 and 15 illustrate in plan view and sections a checking device, see Sheet I.

115

Referring to these drawings, 1 designates a tubular protecting casing of which one end is closed while into the other end, the so-called lamp-head 2, the electric lamp 3 is screwed. 4 is a check lever by means of which a toothed bar 34 adapted to actuate the driving gear is stopped from movement when the apparatus is not used. For the manipulation of the bar 34 a knob 5 is screwed into the same.

120

The closed end of the protecting casing 1 is of a suitable thickness and strength in order to receive and securely hold in a cylindrical recess therein an inductor shaft 6 of which one end extends through a bore in the head part of a magnet 15 which, longitudinally, is of U-shaped section, the other end

125

of the shaft 6 carrying a disk 12. There is also a central axially disposed shaft 7 mounted at the other end of the inductor, this shaft carrying a disk 8 and being hollow and at the right hand end provided with screw-threads, Fig. 3. Leading through the hollow shaft 7 is an electric conductor which is disposed within an insulating sleeve 9 and connected with a contact pin 10, said conductor also extending through another insulating sleeve 46 fitting into the bore of the shaft 7. The disks 12 and 8 are in connection with the inductor 11 which seen in cross section has double T-form, Fig. 5. Wound around the iron core 11 is the wiring 13' which with the core forms the inductor.

The U-shaped magnet 15 is rotatably mounted upon the inductor and, by means of a sleeve 18 secured on the shaft 6, journaled thereon. Attached to the open end of the magnet, that is, to the ends of the two parallel members of the same, by screws 17, is a guiding flange 16, in such a manner, that the magnet 15 with the said flange is also rotatable on the shaft 7. Between the outer end of the inducting magnet 15 and the protecting casing 1 a small space for play is provided. The guiding flange 16 is formed with a nave which carries a toothed wheel 19 adapted to rotate on the shaft 7.

The inductor is connected by bolts with a casing containing the driving gear and consisting of the four parts 20, 21, 22, and 23, Figs. 2 and 3, which are secured to each other and to the protecting casing 1 by the screw-bolts 33 and 37. Of these parts that denoted by 21 contains an insulating sleeve 24 in the one recess of which a set-screw 25 is arranged and made to securely hold a right-angle shaped contact plate 26. The screw 25 engages with, that is, it is screwed into a nut situated within a second recess in the sleeve 24, which nut 27, by means of a spring 28 is in electrical connection with the contact pin 10. The contact plate 26 is connected with a contact blade 30 fixed upon and extending into the insulating disk 23, Fig. 4, and thus forms the electrical connection from the inductor 11 to the electric lamp 3. The contact blade 30 is hereby held fast on the insulating disk 23 by a set-screw 31. One pole of the winding 13 is therefore connected with the one contact of the electric lamp by the members 25, 26, 27 and 30, whereas the other pole of the winding, for instance for an insulating protecting casing, is in electrical connection with the other contact of the electric lamp by means of the parts 11, 8, 7, 21 and the bolt 33, which also secures a contact blade 32 on the insulating disk 23.

The holding fast in position of the toothed bar 34, as already mentioned, is effected by means of the checking lever 4 which is pivotally mounted in the casing 1 and provided

with two diametrically opposite flat surfaces, as at 46, as well as a recess 47 set off somewhat relative the said surfaces. A pin 49 controlled by a spring 48 may be pressed against these surfaces 46 in such a way that the check-lever 4 is prevented from accidental displacement, Fig. 15. The recess 47 can be brought so as to lie in the sliding plane of the toothed bar 34, that is, from the position shown in Fig. 14 into that illustrated in Fig. 15. In the position shown in Figs. 13 and 14 the bar 14 is stopped from movement in the casing. By swinging the checking lever about an angle of 180° the toothed bar is rendered free, owing to the recess 47 being brought into the sliding plane of the bar.

The driving movement takes place in the following manner. The middle portion of an axle or shaft 14, which forms an integral part with the toothed wheel 40, is of square section and carries an axially slidably coupling wheel 42 kept in engagement with the wheel 41 by the spring 43, the wheel 41 being freely and rotatably mounted upon the right-hand cylindrical portion of the shaft 14. The toothed wheel 41 engages with a gear wheel 39, Fig. 11, which is rigidly connected with another gear wheel 38, the latter rotating the toothed wheel 19 and with it the magnet. The toothed bar 34, which is capable of upward and downward movement, engages with the toothed wheel 40. Upon the projecting end of the said bar a handle 5 is screwed.

When the toothed wheel 40 is turned during the downward movement of the bar 34, the coupling wheel 42 will cause the rotation of the wheel 41. If, however, the wheel 42 is rotated in the opposite direction, which is the case when the toothed bar is moved upwards, the wheel 42 only, rotates, because the bevelled faces of the teeth of the wheels 41 and 42 slide away over each other so that the magnet is in no way hindered in its rotation. Part of the coupling wheel 42 is formed as gear wheel. The pinion 39 is carried by a sleeve 44 fixed in the disk 21 and is connected with the gear wheel 38. Both wheels 38 and 39 are journaled in and guided by the disk 20.

The toothed bar 34, which has fixed to it a pin 35 extends through a slot provided in the disk 22, is under the control of a spring 36, Fig. 9, which preferably consists of two or three thin steel blades mounted one upon the other. One end of this spring is secured to the pin 35 of the toothed bar and the other end to one of the screw-bolts 33, with the effect that the toothed bar has the tendency to move upwardly.

When used the apparatus works as follows: Assuming the toothed bar 34 to be moved downwardly by the handle 5, the toothed wheel 40 is made to rotate and,

through the medium of the aforementioned gear wheels a rotation of the inducting magnet caused, so that inducting electric currents are produced which bring about the lighting 5 of the lamp. The spring 36 then causes the toothed bar at once to move upwards again into the former position whereupon the bar is pressed down once more by hand in order to impart a new impulse to the rotary movement of the magnet 15. The actuation of the toothed bar is continued as long as the supply of light is desired.

What I now claim and desire to secure by Letters Patent is:—

- 15 1. In a magneto-electric pocket lamp, the combination, with a tubular protecting casing which is closed at one end and fitted with an electric lamp at the other end, of an inducting magnet rotatably mounted within 20 and at the closed end of the protecting casing, an electric current producing inductor fixed in the magnet, a second casing with driving gear therein mounted within and near the other end of the protecting casing 25 and consisting of several parts held together by two screw-bolts, a shaft axially mounted at each end of the inductor, one of the shafts being journaled in the closed end of the protecting casing and attached to the inductor, and the second and hollow shaft being joined to the other end of the inductor and extending into and bearing in the gear containing casing, an insulating sleeve secured in the outer end of the hollow shaft, a contact pin fixed in this sleeve and enabling electrical connection between one 30 end of the wiring of the inductor and the electric lamp, an insulating contact device mounted in the driving gear casing and adapted to make connection with the lamp by the inner electric circuit while the outer circuit is conducted over the protecting casing, a spring securely clamped by one of the aforementioned screw-bolts and having the 35 tendency to raise a toothed bar from the driving gear casing and cause it to engage with a pinion of the driving gear, a coupling forming part of the driving gear and comprising two coupling wheels of which one is 40 spring-controlled and made to couple with the other when the apparatus is actuated, one of these coupling wheels also meshing with a gear wheel which by means of intermediate gear wheels transmits its movement to another toothed wheel mounted with its nave in a flange secured to 45 the magnet.
- 45 3. In the herein-described magneto-electric pocket lamp, the combination, with a tubular protecting casing which is closed at one end and fitted with an electric lamp at 50 the other end, of an inducting magnet rotatably mounted within and at the closed end of the protecting casing, an electric current producing inductor fixed in the magnet, a second casing, a driving gear therein, an insulating sleeve provided in the gear containing casing, a set-screw arranged within the said sleeve, a contact pin connected by 55 said screw with the sleeve with which one of the ends of the wiring of the inductor is connected, a right-angle-shaped contact plate held by said set-screw, and a contact blade for coaction with said pin for connecting one of the poles of the lamp with the inductor, substantially as and for the 60 purpose described.
- 60 4. In the herein-described magneto-electric pocket lamp, the combination, with a tubular protecting casing which is closed at one end and fitted with an electric lamp at the other end, of an inducting magnet rotatably mounted within and at the closed end of the said casing, an electric current producing inductor fixed in the magnet, a second casing with driving gear therein 65

ing, an electric current producing inductor fixed in the magnet, a second casing with driving gear therein mounted within and near the other end of the protecting casing and consisting of several parts held together 70 by two screw-bolts, a shaft axially mounted at each end of the inductor, one of the shafts being journaled in the closed end of the protecting casing and attached to the inductor, and the second and hollow shaft being 75 joined to the other end of the inductor and extending into and bearing in the gear containing casing, an insulating sleeve secured in the outer end of the hollow shaft, a contact pin fixed in this sleeve and enabling 80 electrical connection between one end of the wiring of the inductor and the electric lamp, a toothed bar mounted in the driving gear casing, a spring securely clamped by one of the aforementioned screw-bolts and having 85 the tendency to raise the said bar from the gear casing and cause it to engage with a pinion of the driving gear, a handle fixed on the toothed bar, means for checking the movement of the same in the protecting casing when the apparatus is not used, and a coupling forming part of the driving gear and comprising two coupling wheels of which one is spring-controlled and made to 90 couple with the other when the apparatus 95 is actuated, one of these coupling wheels also meshing with a gear wheel which by means of intermediate gear wheels transmits its movement to another toothed wheel mounted with its nave in a flange secured to 100 the magnet.

3. In the herein-described magneto-electric pocket lamp, the combination, with a tubular protecting casing which is closed at one end and fitted with an electric lamp at 105 the other end, of an inducting magnet rotatably mounted within and at the closed end of the protecting casing, an electric current producing inductor fixed in the magnet, a second casing, a driving gear therein, an 110 insulating sleeve provided in the gear containing casing, a set-screw arranged within the said sleeve, a contact pin connected by said screw with the sleeve with which one of the ends of the wiring of the inductor is connected, a right-angle-shaped contact plate held by said set-screw, and a contact blade for coaction with said pin for connecting one of the poles of the lamp with the inductor, substantially as and for the 115 purpose described.

4. In the herein-described magneto-electric pocket lamp, the combination, with a tubular protecting casing which is closed at one end and fitted with an electric lamp at 120 the other end, of an inducting magnet rotatably mounted within and at the closed end of the said casing, an electric current producing inductor fixed in the magnet, a second casing with driving gear therein 125

mounted within and near the other end of the protecting casing and consisting of several parts held together by two screw-bolts, a shaft axially mounted at each end of the inductor, one of the shafts being journaled in the closed end of the protecting casing and attached to the inductor, and the other and hollow shaft being joined to the other end of the inductor and extending into and bearing in the gear containing casing, an insulating sleeve secured in the outer end of the hollow shaft, a contact pin fixed in this sleeve and enabling electrical connection between one end of the wiring of the inductor and the electric lamp, a toothed bar mounted in the driving gear casing, a spring securely clamped by one of the aforementioned screw-bolts and tending to raise the toothed bar and cause it to engage with a pinion of the driving gear, a shaft journaled horizontally in the gear casing and parallel to the shaft, the middle part of the shaft being of square section, a coupling comprising two coupling wheels mounted on the latter shaft, one of these coupling wheels being spring-controlled and axially slidable on the square section part of the shaft, while the other coupling wheel, formed with an integral toothed wheel, is made rotatable on the cylindrical portion of the said shaft and engaging with a gear wheel which by means of the toothed wheels cause the rotation of the magnet.

5. In a driving gear for magneto-electric pocket lamp, a driving gear casing comprising detachably coupled part, a toothed bar adapted to move upwards and downwards of the casing, a pin extending through an opening in the casing and fixed to the bar, and a spring consisting of several thin steel blades fixed with one end to the said pin and at the other end to the casing, the spring controlling the movement of the toothed bar.

6. In the herein-described magneto-electric pocket lamp, a gear casing; a toothed bar adapted to move up- and downwards of the casing, a pin extending through an opening in the casing and secured to the bar, a spring consisting of several thin steel blades fixed with one end to the said pin and the other end to the casing; in combination with a check-device comprising a check-lever pivotally mounted in the gear casing and provided with two diametrically opposite flat surfaces and a recess set off relative to these surfaces, and a spring-controlled pin adapted to be pressed against the flat surfaces, a turning of the check-lever allowing of the adjustment of the recess into and out of the plane of the sliding way of the toothed bar for the purpose of checking or freeing its movement.

In testimony whereof I have signed my name to this specification.

IDA HÄGGI.
